United States Patent Office

Des. 223,535
Patented May 2, 1972

223,535

CHAIR

Peter Ghyczy, Stettiner-Str. 6, 2844 Lemfoerde,
Hannover, Germany

Filed Mar. 23, 1970, Ser. No. 22,015

Term of patent 14 years

Int. Cl. D6—02

U.S. Cl. D15—1

Fig. 1.

Fig. 2.

Fig. 4.

Fig. 3.

Fig. 5.

FIG. 1 is a side view of a chair with the backrest folded downwardly in the closed position showing my design.

FIG. 2 is a front view of the chair with the backrest thereof in the closed position.

FIG. 3 is a top view of the chair with the backrest in the closed position.

FIG. 4 is a bottom view of the chair.

FIG. 5 is a view of the back of the base of the chair with the backrest in the closed position.

FIG. 6 is a side view of the chair with the backrest in its upright open position.

FIG. 7 is a front view of the chair with the backrest upright in its open position.

FIG. 8 is a top view of the chair with the backrest in the upright open position.

FIG. 9 is a back view of the chair with the backrest in the upright open position.

FIG. 10 is a bottom view of the chair with the backrest in the open upright position.

I claim:

The ornamental design for a chair, as shown.
